UNITED STATES PATENT OFFICE.

ARCHIBALD J. TURNER, OF CHICAGO, ILLINOIS, ASSIGNOR, BY MESNE ASSIGNMENTS, TO WILSON-WESTERN SPORTING GOODS COMPANY, OF CHICAGO, ILLINOIS, A CORPORATION OF DELAWARE.

HELMET OR HEAD GUARD.

Original application filed May 29, 1924, Serial No. 716,775. Divided and this application filed April 27, 1925. Serial No. 25,963.

The invention relates to helmets or head guards for use by athletes and others, and particularly football players for the protection of the head and parts thereof.

5 This case is a division of my copending case Serial Number 716,775 filed May 29, 1924, for improvements in helmets or head guards.

10 The invention has as its prime object, the utilization of a cushioning material, which is resilient to a great degree, and will, therefore, adequately cushion blows and impacts applied to the head, add to the comfort of the wearer, and is impervious to moisture occasioned by perspiration from the head of the wearer, and consequently will not become matted and lose its resiliency.

15 It is a further feature of the invention to employ a material which has the above qualifications, which can be stamped or cut from a sheet of the material, and, if desired, be provided with ventilating openings and other features.

20 It is therefore an object of the invention to employ in the head guard, a cushion formed of what is generally known as sponge rubber, which, as is well known, contains innumerable minute individual air cells, and is very resilient, impervious to moisture, will not become matted, hardened, or lose its resiliency, as is the case with felt, and therefore will, at all times, be comfortable to the wearer while being worn, will provide a cushion having extremely great 25 cushioning qualities, which cannot be obtained by any other known material, will conform itself to the outlines of the head yet will not, due to irregularities in the shape of the head, exert pressure to annoy or distress the wearer.

30 The invention has the above and other objects, all of which will be explained and more thoroughly understood when read in conjunction with the accompanying drawings 35 which illustrate an embodiment to which the invention is susceptible, it being further obvious that other changes and modifications may be made without departing from the spirit of the appended claims forming a 40 part hereof.

In the drawings:

Figure 1 is a longitudinal central section of a head guard embodying the invention.

Figure 2 is a plan view looking toward

the inside of the head guard shown in Figure 1.

Figure 3 is a plan view of the structure illustrated in Figures 1 and 2.

35 The head guard with which the cushion, which forms the basis of this invention, is associated, is constructed with the relatively stiff leather crown 10, which fits over the top of the head of the wearer and extends approximately to the temples. Reinforcing strips or straps 11 and 12, preferably of leather, are arranged transversely with relation to each other on the exterior of the crown 10 and extend downwardly a short distance beyond the edge of the leather crown 10. These strips or straps are sewed 40 or otherwise secured to the crown 10 of the head guard. Beneath the reinforcing strips 11 and 12 a fibre strip 13 is located. This fibre strip extends from the front to the rear of the crown 10. A suitably shaped 45 piece of material 14, such as fibre, which acts as a stiffener for the head guard, is interposed below the crown 10 and between it and a crown shaped piece of felt 15 or other suitable material. The various parts may 50 be secured together in any suitable manner.

55 The sponge rubber cushion 16 forming the basis of this invention, is located on the interior of the crown of the head guard, and other portions of the head guard structure, 60 so that it may engage the head of the wearer. The sponge rubber cushion 16, being located next to the head of the wearer, will effectively protect the head of the wearer or player against blows or impacts received 65 from opposing players, or otherwise.

70 The sponge rubber blank from which the cushion or lining 16 is formed is clearly shown in Figure 3. It consists of a plurality of separated radially extending arms 17, 75 17, which are connected together at their inner ends to provide a unitary structure. The arms 17, 17, which radiate from the central portion, terminate at their outer ends in the enlargements 18, 18. The radiating 80 arms, with their enlargements, are cut and shaped so that the cushion may be readily inserted into the crown of the head guard and conform with the shape of the interior 85 of the head guard. When the cushion 16 is 90 in place in the interior of the head guard the side faces of the enlargements of the arms 95 contact or engage similar side faces of ad-

adjacent enlargements of the arms. When the side faces of the enlargements of the radiating arms have been brought into juxtaposition, a continuous band of sponge rubber is formed. When the cushion is arranged in the manner described and the opposite side faces of the enlargements of the radiating arms, such as 19, 19, of one of the arms engages with the corresponding side faces, such as 20, 21, of the enlargements of adjacent arms, ventilating openings, such as 22, 22, will be formed in the cushion. The cushion crown or lining shown in Figure 3, and as arranged with the adjacent side faces of the enlargements of the radiating arms, in contact or engagement with each other, is then stitched or otherwise secured to the remainder of the head guard, as indicated at 23. Ventilating apertures 24 are arranged in the relatively stiff leather crown 10, which ventilating apertures extend through the fibre material or stiffener 14 and the crown shaped felt 15. The apertures 24 are placed in alignment and register with the ventilating openings 22, 22, formed as a result of the positioning of the radial arms 17, 17, with their enlargements 18, 18. The apertures 24 and the openings 22 form a means for ventilating the interior of the head guard, and, due to the resiliency of the inner lining or cushion 16, air will be readily drawn in and exhausted from the interior of the head guard upon the compression and the expansion of the cushion 16. The sponge rubber cushion or lining 16 is secured at its center in a suitable manner, as by stitching, as indicated at 25.

The transversely arranged reinforcing cross strips 11 and 12, as before stated, extend downwardly beyond the crown of the head guard a suitable distance, and provide a means whereby the combined head band and ear pieces may be secured to the crown 10. The head band designated 26 is lined with a soft and comfortable material, such as felt, and is formed with the forehead band 27 and the rear section 28, and also the depending cupped ear pieces 29 and 30, so as to protect the front, rear and sides of the player's head, and also his forehead, ears and portions of his cheeks. The forehead band 27 besides being cushioned, is designed to yield so as to compensate for heads of various sizes, and therefore is connected to the head band 26 by means of the resilient elastic bands 31 secured in the forehead band 27. The cupped ear pieces or extensions 29 and 30 are apertured, as indicated at 32, and also at the plurality of apertures 33, 33, so that the hearing of the player will not be interfered with. An elastic strap 34 extends

from the ends of the ear pieces 29 and 30, and this strap is designed to encircle the chin and hold the head guard on the head of the player against accidental removal.

65

From an inspection of Figures 1 and 2 it may be readily seen that the cushion or lining illustrated in Figure 3 is formed so that it may be inserted into the interior of the head or crown portion of the head guard and fit snugly therein, and forming a soft and comfortable cushion covering all rough places on the interior of the crown of the head guard.

70

From the foregoing description it is manifest that the use in a head guard of a cushioning material of the character described, that is, sponge rubber, will have a cushioning effect and action similar to that of a pneumatic cushion; that the material is impervious to moisture resulting from perspiration from the wearer, and that it will conform to the shape of the head of the wearer and will not, at any time, cause undue pressure to be exerted, so as to interfere with the comfort of the wearer or player. Furthermore, it is evident that the sponge rubber cushion will not become matted, and therefore lose its resiliency, as would be the case if some material, such as felt or similar material were employed for the cushion. It is also manifest that the cushion may be readily stamped from a sheet of material into the desired configuration, so as to permit the cushion to be inserted into the interior of the crown of the head guard, and fit the crown of the head of the player. It will also be apparent that the cushion or lining may be produced at relatively low cost.

90

Having thus described the invention, what I desire to secure by Letters Patent is:

A flat pad or sponge rubber for use in a head guard, which pad is formed with a central cushion portion, a plurality of separated arms radiating from said central cushion portion, the outer ends of said radiating arms being enlarged, said enlarged outer ends of said radiating arms being adapted to be arranged adjacent each other to form a crown and an annular band at the base of the crown, and thereby forming a plurality of relatively large apertures in said pad between said central cushion portion and said enlarged outer ends, said apertures so formed being wide at their outer ends and narrowing to their inner ends and being adapted for ventilating purposes when used adjacent ventilating apertures in the crown of said head guard.

105

In witness whereof, I hereunto subscribe my name this 23rd day of April A. D., 1925.

ARCHIBALD J. TURNER.
